CLAIM

The ornamental design for an airwave pressure therapeutic apparatus, as shown and described.

DESCRIPTION

FIG. 1 is a perspective view of an airwave pressure therapeutic apparatus showing my new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is an enlarged view of portion 8 shown in FIG. 1; and, FIG. 9 is an enlarged view of portion 9 shown in FIG. 6. The broken lines in the drawings depicting the airwave pressure therapeutic apparatus are for the purpose of illustrating portions of the article and form no part of the claimed design. The broken lines demarcating the enlarged views form no part of the claimed design.
